(57) **CLAIM**

The ornamental design for a display screen with graphical user interface for medical scheduling, as substantially shown and described.

DESCRIPTION

The single FIGURE is a front view of a user interface for a display screen with graphical user interface for medical scheduling. The broken line on the outer boundary of FIGURE illustrates a display screen and forms no part of the claimed design. The broken lines within the user interface denote environment.

The matter delineated in broken lines forms no part of the claimed ornamental design.
